UNITED STATES PATENT OFFICE.

ADELINE C. PETERSON, OF NEW YORK, N. Y.

UNDERGARMENT.

Application filed January 9, 1924. Serial No. 685,226.

To all whom it may concern:

Be it known that I, ADELINE C. PETERSON, a citizen of the United States, and a resident of the city of New York, borough of 5 Manhattan, in the county and State of New York, have invented a new and Improved Undergarment, of which the following is a full, clear, and exact description.

This invention has relation to wearing apparel and has particular reference to an undergarment which is especially designed for women.

It is generally the practice to support the hose by means of hose supporters attached 10 to the corset, but when corsets are not worn, no comfortable and effective means has been devised for properly supporting the hose.

It is, therefore, the outstanding object of 20 the present invention to provide an undergarment which is equipped with means for supporting the hose from the shoulders of the wearer, whereby the garment proper is relieved from the supporting stresses or 25 strains.

As a further object the invention contemplates in a garment of the character set forth a means for detachably associating the elastic and metal elements of the hose supporting means from the garment when 30 laundering the same.

As a still further object the invention contemplates an undergarment of the character set forth which is extremely simple in its 35 construction, inexpensive to manufacture, and which is highly efficient in its purpose.

With the above recited and other objects in view, the invention resides in the novel construction set forth in the following specification, particularly pointed out in the accompanying drawings, it being understood that the right is reserved to embodiments other than those actually illustrated herein to the 45 full extent indicated by the general meaning of the terms in which the claim is expressed.

In the drawings—

Figure 1 is a view of the garment in applied position.

Fig. 2 is a vertical sectional view through the garment.

Fig. 3 is a fragmentary enlarged vertical sectional view taken approximately on the line indicated at 3—3 in Fig. 2.

Fig. 4 is a fragmentary detail view illustrating the detachable means of connection

between the hose engaging elements and the garment.

Fig. 5 is a sectional view therethrough taken approximately on the line 5—5 of 60 Fig. 4.

Referring to the drawings by characters of reference, 10 designates an undergarment such as a chemise, envelope chemise, or the like, which garments are usually constructed 65 of a very delicate fabric. The garment 10 is provided with shoulder straps 11 which are secured to the waistband 12 and also secured at 13 to the top of the garment. A tab 14 is attached to the inside of the garment at 70 the waistband at opposite sides thereof and said tabs, the lower ends of the shoulders straps 11 and the waistband of the garment are secured together by a common line or lines of stitching 15. A pair of strips 16 of 75 elastic webbing are detachably associated with the lower free end of the tabs and said strips are provided at their lower ends with hose gripping elements 17. The detachable means of connection between the strips 16 80 and the tabs 14 as illustrated consists in the formation of buttonholes 18 in the lower end of the tabs through which the looped elements 19 at the upper end of the strips 16 are inserted. The looped elements 19 are 85 permanently attached as at 20 at one of their ends to the upper end of the strips 16 and are detachably associated at their opposite ends to the upper end of the strip 16 by separable fastening elements 21. This ar- 90 rangement permits of the ready detachment of the hose supporting strips 16 from the garment when it is desired to launder the same.

It will be noted that the point of 95 securing of the shoulder straps 11 is such that the body 22 of the garment has a sufficient slack when the straps 11 are taut as to eliminate the strains or stresses of supporting the hose from the garment proper while said strains or stresses are carried 100 directly by the straps 11, tabs 14 and the strips 16 from the shoulders of the wearer. In order to prevent lateral bulging of the garment at the waistband by the vertical strain and to lend a neater and more attractive appearance to the garment, shirr strings 105 23 are attached to the waistband of the garment and trained through guide tunnels 24, so that the garment may be gathered at the waistband as illustrated.

I claim:

The combination with a woman's under-

garment including a waist portion, of a pair of inverted U-shaped shoulder straps disposed upon the inside of the waist portion of the garment, each of said straps having its lower end connected to the waist band of the garment, said straps being connected to the upper edge of the garment, the under-garment being supported by the shoulder straps and providing for a vertical slack

in the waist portion of the garment so that 10 when the straps are taut they will relieve the garment body of the strains and stresses exerted on the straps supporting the hose, and hose supporting means connected to the band at points on the band where the free 15 ends of each of the straps are connected to said band.

ADELINE C. PETERSON.
